UNITED STATES PATENT OFFICE.

HORACE SEE, OF NEW YORK, N. Y.

ASH-EJECTOR.

SPECIFICATION forming part of Letters Patent No. 581,520, dated April 27, 1897.

Application filed June 25, 1894. Renewed December 15, 1896. Serial No. 615,806. (No model.)

To all whom it may concern:

Be it known that I, HORACE SEE, of the city of New York, in the county and State of New York, have invented certain new and useful 5 Improvements in Ash-Ejectors for Steam Vessels, which invention is fully set forth and illustrated in the following specification and accompanying drawings.

The object of this invention is to provide 10 an efficient hydropneumatic ash-ejector which may be automatically started into operation at the desired time.

The invention will first be described in detail, and then set forth in the claims.

15 Figure 1 of the accompanying drawings shows in sectional side elevation a hydropneumatic ash-ejector embodying my invention. Fig. 2 is a sectional side elevation illustrating a detail of construction hereinafter 20 described.

In said drawings the several parts are respectively indicated by reference-numbers as follows:

1 indicates an ashes receptacle or hopper 25 which may be provided with any suitable cover. The lower part of said hopper is connected to a pipe 2, which in turn is connected to a discharge-pipe 3, leading overboard from the vessel at any suitable point. To the lower

30 part of the discharge-pipe 3 is connected an ejector-nozzle 4, connected to an ejector-pipe leading from any suitable force-pump. The point of the ejector-nozzle 4 where it enters the discharge-pipe 3 is provided with a valve-

35 seat 5, upon which is seated a conical valve 6. Said valve forms an extension of a stem 7, which is connected to a piston 8 9, of differential diameter, located within a cylinder or chamber 10, the portion 8 of said piston

40 being of greater area than the portion 9. The valve-stem 7 is provided near its lower end with an enlargement 11, forming a plunger within a recess 12 in the top of the chamber 10, thus constituting a reverse dash-pot ar-

45 rangement. Said valve-stem is provided with hydraulic packing 13, and the differential piston 8 9 is also provided with hydraulic packing 14 15. The packing 14 is secured by a screw-collar 16 and the packing 15 by a 50 screw-bolt 17 and washer 18.

To the bottom of the differential piston 8 9

is connected, by means of the screw-bolt, if desired, one end of a coiled spring 19, the other end of which may be secured to the bottom of the cylinder or chamber 10. Said spring 55 is only made strong enough to overcome the weight of the valve-stem 7 and piston 8 9 and keep the valve 6 against its seat when there is no pressure in the pipe or nozzle 4.

A pipe 20 connects the ejector-nozzle 4 with 60 the cylinder 10 below the differential piston, and a pipe 21 connects the two ends of said cylinder above and below said piston. The pipe 21 is provided with a valve 22, held closed by a spring 23 until the desired working pressure of water has been obtained in the pipes, when said spring will yield and allow water to pass through the valve 22 into the upper end of the chamber 10, above the piston 8, as hereinafter more fully described. 70

Between the valve 22 and the upper end of the chamber 10 a three-way cock 24 is provided in the pipe 21. Said cock is provided with a lever or handle 25 for operating the same and is so constructed that its plug can 75 be turned so as to admit water into the chamber 10 or to drain into the atmosphere through the nozzle 26. The chamber 10 is provided with a drain-pipe 27 for carrying off any water which may leak past the piston 8 9. 80

Located in the pipe 2, which connects the hopper with the discharge-pipe 3, is an air-valve 28, which may be a spring check-valve or a valve of any suitable construction. The air-valve 28 (shown in section detached in 85 Fig. 2) has a stem 29, provided with a coiled spring 30 within a cap 31, thus constituting a spring check-valve.

Heretofore in hydropneumatic ash-ejectors an air-valve has been placed on the discharge-pipe 3 above the branch 2, but in practice I have found that such location of said valve is not a favorable one, as when the lid of the hopper is closed the ejector does not start in operation because of the vacuum created in 90 the pipe 2. This difficulty I have overcome by locating the air-valve 28 in the position shown in the drawings and admitting air through said valve to the pipe 2, thus destroying the objectionable vacuum in said pipe. 100 The cover of the hopper may thus be kept closed, as is often desirable, when the ejector

is not at work in order to prevent water or other objectionable matter entering the ship through the hopper, which might happen if the lid of the hopper were open when the 5 ejector was not in use.

The operation of the apparatus is as follows: When it is desired to elevate the ashes and discharge the same overboard, the cover of the hopper 1 may, if desired, be first closed, 10 and the handle 25 of the cock 24 is then moved into the position shown in the drawings, and the force-pump connected to the ejector-nozzle 4 is started and water forced into said nozzle. Said water flows through the pipe 20 15 into the lower part of the chamber 10 and from said chamber into the pipe 21. When the pressure of said water is sufficient to compress the spring 23, the valve 22 will open and allow the water to pass through the pipe 21 20 and cock 24 into the chamber 10 above the differential piston 8 9. The area of the upper portion 8 of said piston being greater than the area of the lower portion 9, said piston will be forced downward and the conical valve 25 25 thus released from its seat. The area of the valve and weight of the valve-stem 7 will assist in this downward movement of the piston 8 9, and the spring 19 and compression of water below the piston 9 will prevent a too-sudden 30 den arrest of the same. When the valve 6 has been thus opened, a solid jet of water enters the discharge-pipe 3 through the tapered bore of the nozzle 4 under a very high pressure and with great velocity. The cover of 35 the hopper 1, if closed, is then opened and the ashes thrown into said hopper, from which they pass into the discharge-pipe 3, where they encounter the jet of water entering through the ejector-nozzle 4 and are carried 40 with the water up through said pipe and discharged overboard, this discharge continuing as long as ashes are thrown into the hopper 1.

When the work has been completed and it is desired to close the valve 6, the lever 25 of the cock 24 is moved into the position shown 45 by dotted line 29. Communication is thus shut off between the ejector-nozzle 4 and the upper end of the chamber 10 and communication established between said ejector-nozzle 50 and the atmosphere through the nozzle 26. The pressure of water in the chamber 10 will then be sufficient to elevate the piston 8 9 and close the valve 6. The conical or pointed end of said valve in this upward movement will 55 force out any foreign matter which may have lodged in the ejector-nozzle 4. The plunger 11 and dash-pot 12 will prevent the too-sudden seating of the valve 6.

The construction above described presents 60 the advantage of automatically and quickly opening the ejecting-valve of an ash-ejector by simple mechanism, an advantage which is of considerable importance, as it has been found that in an ash-ejecting apparatus in 65 order to start the machine into operation with certainty it is necessary that said valve should

be opened very suddenly under a great pressure of water.

If it be desired to operate the apparatus by hand instead of automatically, as above described, the chamber 10 and its inclosed parts may be dispensed with and the stem 7 of the valve 6 made to pass through a stuffing-box outside of the ejector-pipe 4, said stem being controlled in such case by any of the well-known means for opening and closing valves; but it is deemed preferable to use the automatic starting mechanism above described.

Having thus fully described my invention, I claim—

1. In a hydropneumatic ash-ejecting apparatus, the combination of an ash receptacle or hopper; a discharge-pipe; an ejector-pipe or nozzle, provided with a single discharge-opening; a valve for said opening provided 85 with a stem extending downward through said pipe or nozzle; and means substantially as described, connected to the lower end of said stem for operating said valve.

2. In a hydropneumatic ash-ejecting apparatus, the combination of an ash receptacle, or hopper; a discharge-pipe; an ejector-pipe; a valve for said ejector-pipe provided with a stem; a cylinder or chamber; and a differential piston in said chamber connected to 95 said valve-stem and adapted to be moved by the pressure of the ejecting-water.

3. In a hydropneumatic ash-ejecting apparatus, the combination of an ash receptacle, or hopper; a discharge-pipe; an ejector-pipe; 100 a valve for said ejector-pipe provided with a stem; a cylinder or chamber; a differential piston in said chamber connected to said valve-stem and adapted to be moved by the pressure of the ejecting-water; and a spring 105 connected to said piston to take the weight of the same.

4. In a hydropneumatic ash-ejecting apparatus, the combination of an ash receptacle, or hopper; a discharge-pipe; an ejector-pipe; 110 a valve for said ejector-pipe; and an independent valve provided with a closing-spring and arranged within an exterior pipe connected to said ejector-pipe, so that the opening of said independent valve by the pressure 115 of the water in said exterior pipe will effect the opening of the valve in said ejector-pipe.

5. In a hydropneumatic ash-ejecting apparatus, the combination of an ash receptacle, or hopper; a discharge-pipe; an ejector-pipe; 120 a valve for said ejector-pipe provided with a stem; a cylinder or chamber provided with a differential piston connected to said valve-stem; a pipe connecting said ejector-pipe with 125 said chamber; and a valve in said pipe held closed until the desired pressure of ejecting-water has been obtained.

6. In a hydropneumatic ash-ejecting apparatus, the combination of an ash receptacle, or hopper; a discharge-pipe; an ejector-pipe; 130 a valve for said ejector-pipe, provided with a stem; a chamber or cylinder provided with a

differential piston connected to said valve-stem; a pipe connecting said ejector-pipe with said chamber and provided with a cock; and a lever or handle for operating said cock for the purposes set forth.

5 7. In a hydropneumatic ash-ejecting apparatus, the combination of an ash receptacle, or hopper; a discharge-pipe; an ejector-pipe; a valve for said ejector-pipe, provided with a stem; a chamber or cylinder provided with a differential piston connected to said valve-stem; a pipe connecting said ejector-pipe with said chamber; a valve in said pipe held closed until the desired pressure of the ejecting-water has been obtained; a three-way cock in said pipe; and a lever or handle for operating said cock, for the purposes set forth.

10 8. In a hydropneumatic ash-ejecting apparatus, the combination of an ash receptacle or hopper; a discharge-pipe; an ejector-pipe; a pipe connecting said ash-receptacle with

said discharge-pipe; and an air-valve located in said connecting-pipe and held to its seat by a spring until a vacuum forms in said pipe, when it automatically opens, as and for 25 the purposes set forth.

9. In a hydropneumatic ash-ejecting apparatus, the combination of an ash receptacle or hopper; a discharge-pipe; an ejector-pipe; and a valve for said ejector-pipe provided with a pointed or conical end for the purposes set forth.

15 10. In a hydropneumatic ash-ejecting apparatus, the combination of an ash receptacle or hopper, a discharge-pipe; an ejector-pipe; 35 a valve for said ejector-pipe provided with a stem; and a dash-pot and plunger for said valve, for the purposes set forth.
